UNITED STATES PATENT OFFICE.

JOHN T. HUME, OF CHICAGO, ILLINOIS, ASSIGNOR TO HURLEY MACHINE COMPANY, OF CHICAGO, ILLINOIS, A CORPORATION OF ILLINOIS.

IRONING MACHINE.

Application filed December 16, 1920. Serial No. 431,144.

My invention relates to ironing machines, more particularly but not necessarily those intended for household use, and the object thereof is to produce a simple and efficient machine of this character containing improvements in the matter of manufacture and in mode of operation as well as in facility and convenience of operation and control by the operator. Another object of my invention is to provide a structure in which the ironing machine proper may be properly positioned or aligned regardless of any unevenness in the floor or support.

In the drawings, Fig. 1 is an elevation of one end of the machine; Fig. 2 a section on the line 2—2 of Fig. 3; Fig. 3 a side elevation of the machine; Fig. 4 an elevation of one end of the machine showing two cover plates removed to expose the mechanism within; Fig. 5 a section on the line 5—5 of Fig. 9; Fig. 6 a section on the line 6—6 of Fig. 3 but on a larger scale; Figs. 7 and 8 detail views illustrating a modified form of end frames or brackets; Fig. 9 a section on the line 9—9 of Fig. 4 but on a larger scale, with cover plates restored; Fig. 10 a plan view of one of the operating handles; Fig. 11 a section on the line 11—11 of Fig. 9; Fig. 12 a section on the line 12—12 of Fig. 5; Fig. 13 a section on the line 13—13 of Fig. 5; Figs. 14 and 15 sections on the same line in Fig. 13 but looking in opposite directions as indicated by the arrows corresponding in number to said figures; Fig. 16 a section on the line 16—16 of Fig. 1; Fig. 17 a top plan view of one of the control handles; Fig. 18 a bottom plan view thereof and Fig. 19 a section on the line 19—19 of Fig. 17.

Referring to the present embodiment of my machine as herein shown the same comprises the main supporting frame or end legs 1 connected together by the tie rods 2, the end frames or brackets 3, the roll 4 rotatably mounted therein and the shoe 5 cooperating with the roll, together with the operating and control mechanism hereinafter explained in detail.

The ironing machine proper is supported upon the frame composed of the legs 1 and rods 2 in such a manner that any unevenness of the floor, which of course is communicated to this frame, is not communicated

to such machine proper with the result that the machine is in proper position or alignment and is not placed under any strain and is not distorted. To this end the machine has what may be termed a three point suspension. At one end, as shown in Fig. 4, the end frame or bracket 3 rests solidly upon its supporting leg 1 and is secured thereto in suitable manner as by means of the bolts 6 passing through flange 1^a on said leg. The bracket at the other end of the machine, as shown in Fig. 1, is not so supported but is supported in such a way as to have a rocking movement on the top of its leg 1. As shown in Fig. 1 this is accomplished by providing the leg at this end of the machine with an upwardly extending flange 1^b having a pivotal connection with its bracket by means of a bolt 7. Also there is provided a clearance space between the bottom of the bracket and the top of the leg, so than any unevenness or distortion in the supporting frame is not communicated to the machine itself. These brackets are connected together by means of the tie rods 8 held thereto by set screw 8^a and also by the shafts hereinafter described.

The shoe 5 is of the proper shape to cooperate with the roll and is provided with a hollow portion or heating chamber heated by the gas burners 9 for heating the shoe proper. This shoe is provided at its opposite ends with operating mechanism which is similar in construction and operation, and hence the description of one mechanism will apply to both. The shoe is provided at each end with a depending arm 10 which is operatively connected with its actuating mechanism. Referring more particularly to Figs. 2, 3 and 6, a rock shaft 11 is suitably mounted in the brackets 3 and provided with a yoke secured thereto and including two parallel arms 12, there being of course one yoke for each such mechanism as shown in Fig. 3. This yoke is connected through these arms 12 with the shoe through the medium of a yielding collapsible connection which comprises a link 13, two telescoping heads 14 and 15, Fig. 2, and an interposed spring 16. The link 13 is pivoted at its inner end to the bolt or pin 17, and has at its outer end a slot 18 to receive the transverse pin 19 which also passes through the

head 14. The link is also pivotally connected with the lower end of the shoe extension 10 by means of links 20 pivoted at their upper ends upon the pins 19 and each having a slot 21 to receive the pin or stud 22 projecting laterally from the lower end of such extension or arm 10.

As a result of this connection between the rock shaft 11 and the shoe, such shoe is permitted to have several desired movements or adjustments. When the parts are in the position shown in Fig. 6 the construction is such that the spring 16 imparts a certain predetermined pressure to the shoe and consequently to the roll. When the rock shaft is oscillated slightly the shoe will be moved slightly away from the roll on the pivot 22 as a center. On further oscillation of the shaft 11 the entire shoe, including its extension 10, is moved bodily to the left to the position shown in dotted lines in Fig. 1. On the first movement of the rock shaft the spring pressure on the shoe is relieved because of the movement of the pin 19 in the slot 18. At this time the movement of the link 20 has no effect upon the shoe by reason of the provision of the slot 21. On further oscillation of the rock shaft the pin 19 will engage the outer end of the slot 18 and move the shoe to its initial position at which time it rocks on the pin 22 as a center. At this time the pin 22 is located in the bottom of the slot 21 and upon further oscillation of the rock shaft the links 13 and 20 will be caused to withdraw the shoe bodily from the roll. During these movements the pin 22, carried by the arm 10, travels in a slot 22^a formed in the end bracket 3, as illustrated particularly in Figs. 1 and 6. When the shoe 5 engages the padded roll 4 the pin 22 rests at the lower end of the slot 22^a, as illustrated in Fig. 6.

The machine is power driven, in the present instance by the electric motor 23 operatively connected with the roll and also with the rock shaft 11 by mechanism which is under the convenient operation and control of the operator as hereinafter described in detail. This motor is preferably secured 50 to the underside of the feed table 24 which is supported on the upper ends of the bracket 3.

Describing the connecting mechanism between the motor and the roll, the motor is adapted to drive a main driving shaft 25 which may be the extended armature shaft as shown or a separate shaft coupled thereto. Referring to Fig. 4 this shaft, which passes through the bearing 26, has at its inner end a worm 27 meshing with a worm gear 28 secured to a shaft 29. On this shaft and adjacent gear 28 is a pinion 30 which meshes with and drives the gear 31 secured to a shaft 32. On this shaft 32 there is also secured two gears 33 and 34, the

former being the larger. These gears 33 and 34 are in constant mesh respectively with two gears 35 and 36 which are loosely mounted upon a shaft 37 and of which the gear 36 is the larger.

Upon the shaft 37 there is mounted to slide longitudinally a clutch sleeve 38 adapted to be shifted in one direction or the other by the operator and thereby placed in operative engagement with either the gear 35 or gear 36. This sleeve is splined to the shaft 37 and the position shown in Fig. 9 is its neutral position. It is provided with a plurality of clutch jaws on opposite sides, the jaws 39 being adapted to cooperate with the complementary jaws 40 on the gear 35 and the jaws 41 on the other side of the sleeve cooperating with the complementary jaws 42 on the gear 36. When the sleeve is shifted by the operator into engagement with one or the other of the two gears 35, 36 such gear will be operatively connected to the shaft 37 and will be driven thereby. This shaft is provided at its inner end with a pinion 43 which meshes with the main driven gear 44 secured to one end of the shaft 45 of the roll.

The gears and shafts hereinbefore described with the exception of the gears 43 and 44 are mounted within and enclosed by an outer casing 46 suitably secured to the main casing 47 and having an outer removable cap or cover 48. In the present instance the main casing is formed as part of one of the end brackets 3.

Describing the means for shifting the sleeve 38, a vertical rod 49 is mounted to oscillate in a bushing 50 which is held within a top opening in the casing 46 by a set screw 51. This rod is provided at its lower end with a block or disk 52 provided on its lower side with an eccentric pin 53 which is at all times positioned in the circumferential groove 54 of the sleeve 38. The cap 55 fits over the top of the rod 49 and is secured thereto by the screw 56. This cap is provided with a suitable handle 57 and a pointer 58 which is adapted to point to the "slow", "off" and "fast" positions indicated on the stationary plate 59 secured to or forming a part of the bushing 50. The parts described are held with a yielding pressure by means of a coil spring 60 interposed between the lower ends of the bushing 50 and the block 52. Obviously when the operating handle is in the "off" position as shown in Figs. 9 and 10, the sleeve 38 is in neutral position and consequently even if the gears 35 and 36 are rotating the power is not transmitted to the shaft 37. However, when the handle is turned to "slow" position the sleeve 38 is shifted to the right, bringing the clutch jaws 41 and 42 into engagement and making the driving connection through the gears 34 and 36 for the de-

sired slow speed. When the handle 57 is turned to "fast" position the jaws 39 and 40 are brought into engagement and the drive is thereupon through the gears 33 and 35 for the desired high speed.

Next describing the operating connections cooperating with the rock shaft 11, the gear 31 meshes with a pinion 61 secured to a shaft 62 mounted in the lower end of the casing 10 46. This shaft is provided at its inner end with a bevel gear 63 meshing constantly with similar bevel gears 64 and 65 which are loosely mounted upon a shaft 66. This latter shaft extends at right angles to the shaft 62 and is 15 suitably journaled in a casing 67, these forming an extension of the main casing 47, Figs. 4 and 5. The shaft 66 is provided towards its outer end with a worm 68 which meshes with a segmental worm gear 69 secured to one 20 end of the rock shaft 11. In the present instance this gear 69 is mounted within a casing 70 which forms a part of one of the end brackets and the casing 67. The shaft 66 is provided with a thrust ball bearing 71.

Control mechanism is provided in this operating connection for the shaft 11, the same being under the control of the operator whereby when the handle is turned to any one of certain different positions the shoe is 30 moved by the power of the motor to its different described positions. As shown in Figs. 5 and 13 a shifting sleeve 72 is splined to the shaft 66 and is provided on one side with clutch jaws 73 cooperating with complementary clutch jaws 74 on the gear 64 and with clutch jaws 75 cooperating with clutch jaws 76 on the other gear 65. This sleeve is shown in its neutral position in Fig. 5 and consequently the power 40 of the motor is not transmitted from shaft 62 to shaft 66 inasmuch as the gears 64 and 65 will now rotate idly on the latter shaft. The sleeve is shifted by means of a long lever 77 pivoted at its upper end at 78 and having intermediate its length a laterally extending pin or roller 79 which is at all times positioned in the circumferential groove 80 of such sleeve. For swinging this lever in one direction or the other so as to operatively 45 connect one side or the other of the jaws the following mechanism is provided:

A vertical tube 81 has its bearings in the casing 47 and is provided near its lower end with a gear having a single tooth 82 adapted 55 to mesh with the two teeth of a horizontally positioned sliding rack 83 mounted in the lower end of the casing 47, preferably in an oscillating block 84 to accommodate the slight angular movements of this rack. The 60 other end of the rack opposite its teeth is pivotally connected to the lever 77 by pivot pin 85. In order to maintain the lever 77 in its neutral position I provide a yielding plate 86 pivoted at 87 to one side of the casing 65 47 and having on its upper edge a notch 88

which is adapted to receive and yieldingly hold a roller 89 extending laterally from one side of the lever 77 and near its lower end.

The controlling handle comprises a handle 90 having a bowl shaped portion 91 secured to the upper end of this tube whereby the sleeve 72 may be shifted in one direction or the other as desired. This tube surrounds a vertical shaft 92 having near its lower end a worm gear 93 meshing with a worm 94 70 on the shaft 66. The shaft 92 carries at its upper end a disk 95 secured to such shaft and having depending stops 96, 97 and 98, the stop 96 being permanent and the stops 97 and 98 being adjustably mounted on the 75 disk. The stop 96 which depends from the underside of the disk is adapted to cooperate with a stop 99 located at one side of the bottom of the bowl portion 91 of the handle. The two stops 97 and 98 are similar. As 80 shown in Fig. 19 each such stop has a limited vertical movement and its position is maintained by the spring pressed plunger 100 bearing in a slot 101 in one side thereof. This stop is provided at its top with a head 90 102 for hand manipulation. In its position shown in Fig. 19 the stop 97 is in its operating position and adapted to cooperate with the stop 99. However, when it is desired that the other stop 98 or the stop 96 shall be 95 the one to cooperate with stop 99 the stop 97 is drawn upwardly so that it will clear the stop 99 and permit either one of the other two stops to cooperate therewith.

Assuming that it is desired to shift the shoe bodily to its outermost position the handle 90 is turned in one direction or the other as desired with the result that the lever 77 is oscillated so as to shift the sleeve 72 in the corresponding direction and thereby rotate the shaft 66 as determined by which of the two sets of clutch jaws are then brought into engagement. As soon as the shaft 66 begins to rotate the vertical shaft 92 will be 100 rotated thereby correspondingly rotating the disk 95. Assuming that the stops 97 and 98 are both raised to their inoperative positions, the disk in its rotation will cause the stop 96 to engage the projection 99 whereupon the handle will be automatically oscillated and 105 restored to neutral position and likewise the sleeve 72 will be restored to such neutral position. When the stop or projection 96 is the operative one the disk 95 will have substantially a complete rotation before it takes up 110 the handle and carries it back to normal position. However when either one of the two stops 97 and 98 are made operative the handle will be automatically operated at 115 earlier times with the result that the shoe will not be given its extreme position but one of the other desired positions.

As shown in Figs. 7 and 8, one of the end brackets may be so made as to leave one 120 end of the roll free or exposed thereby 125 en-

abling the operator to iron collars and cuffs and also neckbands, and other parts of garments whose other portions do not require ironing. For this purpose one of the end brackets 103 has an inturned portion 104 beginning below the low plane of the roll 4, which portion then extends vertically to support the table 24. A bearing arm 105, preferably integral, extends outwardly and then laterally to form a bearing for that end of the roll. In this manner and by this simple construction, this end of the roll is free and exposed for the purposes stated.

I claim:

1. In an ironing machine, the combination of a supporting frame having parts arranged to rest on a floor, and a main frame for carrying the mechanism of the machine, said main frame having a three-point support on said supporting frame.

2. In an ironing machine, the combination of a supporting frame having parts arranged to rest on a floor, and a main frame for carrying the mechanism of the machine, said frame being firmly mounted at two points on said supporting frame and being loosely mounted at a third point on said supporting frame.

3. In an ironing machine, the combination of a supporting frame having parts adapted to rest on a floor, and a main frame for carrying the mechanism of the machine, such main frame being secured rigidly at one end to the supporting frame and at its other end secured loosely thereto.

4. In an ironing machine, the combination of a supporting frame including two opposite end legs, one of which has an upwardly extending flange, a main frame adapted to carry the mechanism of the machine and including end brackets, one of which has a portion positioned parallel to the flange, and means for pivoting said bracket onto the flange.

5. In an ironing machine, the combination of a supporting frame including two opposite end legs, one of which has an upwardly extending flange, a main frame adapted to carry the mechanism of the machine and including end brackets, one of which has a portion positioned parallel to the flange, and a bolt for connecting said bracket and flange and forming a pivot therefor.

6. In an ironing machine, the combination of relatively movable ironing elements, power means for effecting movement of one of said elements to different positions, operating connections between said power means and said last mentioned ironing element including a disconnecting and reversing mechanism, a device under the control of the operator for operating said mechanism, and automatic means for restoring said device to normal position and thereby disconnecting said mechanism, said device includ-

ing an operating member having a projection, a rotatable member having a stop adapted to cooperate with said projection and operatively connected with the operating connections for restoring said device to normal position and disconnecting said mechanism.

7. In an ironing machine, the combination of relatively movable ironing elements, power means for moving one of said elements to different positions, operating connections between said power means and said last mentioned ironing element including a disconnecting and reversing mechanism, a device under the control of the operator for operating said mechanism, and automatic means for restoring said device to normal position and thereby disconnecting said mechanism,

80

75

8. In an ironing machine, the combination of relatively movable ironing elements, power means for moving one of said ironing elements to different positions, operating connections between said power means and said last mentioned ironing element, including a disconnecting mechanism, a device under the control of the operator for operating said mechanism, and automatic means for restoring said device to normal position and thereby disconnecting said mechanism, said device including an operating member having a projection, a rotatable member having a series of stops to cooperate with said projection, one of said stops being adjustable to be rendered operative or inoperative at will, and means for driving said rotatable member from said power means.

90

95

8. In an ironing machine, the combination of relatively movable ironing elements, power means for moving one of said ironing elements to different positions, operating connections between said power means and said last mentioned ironing element, including a disconnecting mechanism, a device under the control of the operator for operating said mechanism, and automatic means for restoring said device to normal position and thereby disconnecting said mechanism, said device including an oscillating shaft moved by the operator and provided with a gear tooth, a rack bar operated by said tooth, and a lever connected with said rack bar and cooperating with said mechanism for causing operation of said mechanism.

100

105

9. In an ironing machine, the combination of relatively movable ironing elements, power means for moving one of said ironing elements to different positions, operating connections between said power means and said last mentioned ironing element including a disconnecting mechanism, a device under the control of the operator for operating said mechanism, and automatic means for restoring said device to normal position and thereby disconnecting said mechanism, said device including an oscillating tubular shaft operatively connected with said mechanism and a handle at the end of said shaft, said automatic means including an inner shaft within said tubular shaft and a disc secured to said inner shaft and having projections cooperating with said handle, said inner shaft being operatively connected with said mechanism.

110

115

120

125

10. In an ironing machine, the combination of a frame, a roll and a shoe mounted therein, and power means for operating the

- shoe to different positions comprising a rock shaft to which the shoe is operatively connected, a motor, and operating connections between the motor and rock shaft including a disconnecting and reversing mechanism, a device under the control of the operator for operating such mechanism and automatic means for restoring such device to normal position and thereby disconnecting such mechanism, said device including a handle having a projection, a rotatable disk having a stop adapted to cooperate with such projection and operatively connected with the operating connections for restoring said device to normal position and disconnecting said mechanism.

11. In an ironing machine, the combination of a frame, a roll and a shoe mounted therein, and power means for operating the shoe to different positions comprising a rock shaft to which the shoe is operatively connected, a motor, and operating connections between the motor and rock shaft including a disconnecting and reversing mechanism, a device under the control of the operator for operating such mechanism and automatic means for restoring such device to normal position and thereby disconnecting such mechanism, said device including a handle having a projection, a rotatable disk having a series of stops, one or more of which are adjustable so as to be rendered operative or inoperative at will, said stops cooperating with said projection and said disk being actuated by the operating connections.

12. In an ironing machine, the combination of a frame, a roll and a shoe mounted therein, and power means for operating the shoe to different positions comprising a rock shaft to which the shoe is operatively connected, a motor, and operating connections between the motor and rock shaft including a disconnecting and reversing mechanism, a device under the control of the operator for operating such mechanism and automatic means for restoring such device to normal position and thereby disconnecting such mechanism, said device including a handle having a projection, a rotatable disk having a series of stops, one of which is permanent and another of which is adjustable, said projections and stops cooperating to determine the length of time of operation of such mechanism, said disk being connected with the operating connections.

13. In an ironing machine, the combination of a frame, a roll and a shoe mounted therein, and power means for operating the shoe to different positions comprising a rock shaft to which the shoe is operatively connected, a motor, and operating connections between the motor and rock shaft including a disconnecting and reversing mechanism, a device under the control of the operator for operating such mechanism and automatic means for restoring such device to normal position and thereby disconnecting such mechanism, said device including a handle having a projection, a rotatable disk having a series of stops, one of which is permanent and another of which is adjustable, said projections and stops cooperating to determine the length of time of operation of such mechanism, said disk being connected with the operating connections.

14. In an ironing machine, the combination of a frame, a roll and a shoe mounted therein, and power means for operating the shoe to different positions comprising a rock shaft to which the shoe is operatively connected, a motor, and operating connections between the motor and rock shaft including a disconnecting and reversing mechanism, a device under the control of the operator for operating such mechanism and automatic means for restoring such device to normal position and thereby disconnecting such mechanism, such device including an oscillating shaft moved by the operator and having a gear tooth, a sliding rack operated by such tooth, a lever connected with the rack and cooperating with such mechanism for causing operation of the rack and also disconnection.

15. In an ironing machine, the combination of a frame, a roll and a shoe mounted therein, and power means for operating the shoe to different positions comprising a rock shaft to which the shoe is operatively connected, a motor, and operating connections between the motor and rock shaft including a disconnecting and reversing mechanism, a device under the control of the operator for operating such mechanism and automatic means for restoring such device to normal position and thereby disconnecting such mechanism, such device including an oscillating tubular shaft operatively connected with such mechanism, a handle at one end of the shaft, and said automatic means including an inner shaft within the tubular shaft, a disk secured to the top of the inner shaft and having projections cooperating with the handle, such inner shaft being operatively connected with said mechanism.

16. In an ironing machine, the combination of a frame including end brackets and a roll mounted therein, one of the said brackets having an inturned portion beginning below the lower plane of the roll and extending inwardly from the end of such roll to thereby expose such end.

17. In an ironing machine, the combination of a frame including end brackets and a roll mounted therein, one of the said brackets having an inturned portion beginning below the lower plane of the roll and extending inwardly from the end of such roll to thereby expose such end, said inturned portion having a bearing arm for that end of the roll.

18. In an ironing machine provided with ironing elements and supporting and operating means therefor, a frame including two side members and upon which said ironing elements and their supporting and operating means are mounted, a base, and means for pivotally supporting one of said side members upon said base.

19. In an ironing machine provided with ironing elements and supporting and operating means therefor, a support upon which said ironing elements and their supporting and operating means are mounted, said support including two side frames each including two legs adapted to rest upon the floor, one of said side frames being formed in two pivotally connected parts whereby the ironing elements and their supporting and

operating means are provided with a three-point support.

19. In an ironing machine provided with ironing elements and supporting and operating means therefor, a frame including two side members and upon which said ironing elements and their supporting and operat-

ing means are mounted, one of said members being provided with two legs adapted to rest on the floor, a base provided with two legs also adapted to rest on the floor, and means for pivotally supporting the other of said side members upon said base. 10

JOHN T. HUME.
